(57) **CLAIM**

The ornamental design for an optical sensor array liner with optical sensor array pad, as shown and described.

DESCRIPTION

FIG. 1 is a front, right perspective view of an optical sensor array liner;

FIG. 2 is a front view of the optical sensor array liner;

FIG. 3 is a back view of the optical sensor array liner;

FIG. 4 is a left side view of the optical sensor array liner;

FIG. 5 is a right side view of the optical sensor array liner;

FIG. 6 is a top view of the optical sensor array liner;

FIG. 7 is a bottom view of the optical sensor array liner;

FIG. 8 is a front, right perspective view of the optical sensor array liner of FIG. 1 positioned on an optical sensor array;

FIG. 9 is a front, right perspective view of an optical sensor array pad;

FIG. 10 is a front view of the optical sensor array pad;

FIG. 11 is a back view of the optical sensor array pad;

FIG. 12 is a left side view of the optical sensor array pad;

FIG. 13 is a right side view of the optical sensor array pad;

FIG. 14 is a top view of the optical sensor array pad;

FIG. 15 is a bottom view of the optical sensor array pad;

FIG. 16 is a front, right perspective view of the optical sensor array pad of FIG. 9 positioned on the optical sensor array liner of FIG. 1; and,

FIG. 17 is a front, right perspective view of the optical sensor array pad of FIG. 9 positioned on the optical sensor array liner of FIG. 1 positioned on an optical sensory array.
The evenly spaced dashed lines depict unclaimed environment.
